ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

INTERNAL COMBUSTION ENGINE

Application filed January 30, 1928. Serial No. 250,369.

This invention relates to internal combustion engines and refers more particularly to sleeve valve and like types of engines.

One object of my invention resides in an engine construction wherein the sleeve valve mechanism is carried by the cylinder block as distinguished from the crank case. Thus in assembling or removing the cylinder block the sleeve valve mechanism including the sleeve valves and driving layshaft remain assembled with the cylinder block. The relative timing of the sleeve valves is thus not disturbed and the cylinder walls, pistons, and other of the engine parts are more readily accessible for inspection or repair.

A further feature of my invention resides in a construction whereby the layshaft may be readily engaged and disengaged with relation to the layshaft driving mechanism.

20 A still further feature of my invention resides in a sleeve valve mechanism supporting means engageable with the cylinder block on one side of the longitudinal plane of the engine including the cylinder axes. Such construction provides for simplicity, convenience of assembly or disassembly, and relatively small cost of manufacture.

Further objects and advantages of my invention will be apparent as the following 30 description and claims relating to my invention progress.

Referring to the accompanying drawings,

Fig. 1 is a sectional elevation view through a typical cylinder showing the sleeve valve 35 driving mechanism,

Fig. 2 is a bottom plan sectional view through the layshaft, and

Fig. 3 is a detail perspective view of the 40 layshaft supporting bracket.

In the drawings A represents the cylinder block having ported cylinders 10, cylinder heads 11, and pistons 13, all of which parts may in general be of the usual or other preferred suitable construction.

45 The engine illustrated is of the single sleeve valve "Burt-McCollum" type in which a ported single sleeve valve 14 has a combined reciprocating and oscillating movement with respect to the sleeve and cylinder axes.

50 The crankcase B has a bearing 15 journal-

ling the layshaft drive shaft 16 provided with suitable means driven by the crankshaft such as the gear 17. The layshaft 18 is driven by shaft 16 through an Oldham coupling 17^a or other coupling permitting ready engagement and disengagement of the shafts 16 and 18 on assembly or disassembly of the cylinder block. The layshaft is journaled at intervals in bearings 19 carried by the bracket C formed with an upper face 20 engageable beneath the laterally projecting portion 21 of the cylinder block A. Studs 22 passing through bracket openings 22^a serve to hold bracket C in its assembled position as shown in Fig. 1. The bearings 19 have bearing caps 23 secured thereto by studs 24 engageable through bosses 25 formed on bearings 19 and caps 23.

The layshaft 18 has spaced ball cranks 26 receiving socket portions of links 27 pivotally connected at 28 to and between the laterally projecting sleeve valve lugs 29.

In operation the shaft 16 will drive the layshaft 18 which in turn moves the links 27 so as to cause the link to occupy successive parallel positions. Thus each sleeve valve is given a combined reciprocating and oscillating movement causing the sleeve and cylinder ports to function in the well known manner. On removal of the cylinder block for example, the layshaft 18, links 27, sleeve valves 14, and bracket C will also be removed as a unit with the cylinder block, the coupling 17^a facilitating such operation.

What I claim as my invention is:

1. An engine of the sleeve valve type comprising in combination, a cylinder block, sleeve valve means operable within the cylinder block, driving mechanism for the sleeve valve means including a layshaft positioned to one side of the longitudinal plane of the engine including the sleeve axes, a crank case construction beneath the cylinder block housing the driving mechanism, driving means for the layshaft, means journaling the layshaft with the cylinder block, and a coupling device between the layshaft and layshaft driving means whereby the layshaft and driving means may be removed as a unit with

the cylinder block from the crankcase construction.

2. An engine of the sleeve valve type comprising in combination, a cylinder block, sleeve valve means operable within the cylinder block, driving mechanism for the sleeve valve, means including a layshaft positioned to one side of the longitudinal plane of the engine including the sleeve axes, a crank case construction beneath the cylinder block housing the driving mechanism, driving means for the layshaft, means journalling the layshaft with the cylinder block, and a coupling device between the layshaft and layshaft driving means whereby the layshaft and driving mechanism may be removed as a unit with the cylinder block from the crankcase construction, said layshaft driving means being journalled in the crankcase construction.
- 10 3. An engine of the sleeve valve type comprising in combination, a cylinder block, sleeve valve means operable within the cylinder block, driving mechanism for the sleeve valve means including a layshaft positioned to one side of the longitudinal plane of the engine including the sleeve axes, a crank case construction beneath the cylinder block housing the driving mechanism, driving means for the layshaft, means journalling the layshaft with the cylinder block, and a coupling device within the crankcase construction between the layshaft and layshaft driving means whereby the layshaft and driving mechanism may be removed as a unit with the cylinder block from the crank case construction.
- 20 4. An engine of the sleeve valve type comprising in combination, a cylinder block, sleeve valve means operable within the cylinder block, driving mechanism for the sleeve valve means including a layshaft positioned to one side of the longitudinal plane of the engine including the sleeve axes, a crank case construction beneath the cylinder block housing the driving mechanism, driving means for the layshaft, means journalling the layshaft with the cylinder block, and a bracket secured beneath the cylinder block and located to one side of the longitudinal plane of the engine including the sleeve axes, said bracket journalling the layshaft, a drive shaft for the layshaft, and a coupling device between the drive shaft and layshaft.
- 30 5. A sleeve valve engine comprising a cylinder block, single sleeve valves movable within said block in a combined reciprocating and oscillating path, a layshaft extending longitudinally of the engine to one side of the sleeve valves, a crankcase structure housing the layshaft, said layshaft having spaced cranks, links connecting the layshaft cranks and sleeve valves tangentially with the latter for imparting the aforesaid movement to the sleeve valves, and means journalling and supporting the layshaft from and beneath the cylinder block said means engaging the layshaft intermediate the spaced cranks.

6. A sleeve valve engine comprising a cylinder block, single sleeve valves movable within said block in a combined reciprocating and oscillating path, a layshaft extending longitudinally of the engine to one side of the sleeve valves, a crankcase structure housing the layshaft, said layshaft having spaced cranks, links connecting the layshaft cranks and sleeve valves tangentially with the latter for imparting the aforesaid movement to the sleeve valves, and means journalling and supporting the layshaft from and beneath the cylinder block, said journalling and supporting means being positioned above the layshaft and extending longitudinally of the engine at the said side of the sleeve valves, said means engaging the layshaft intermediate the spaced cranks.

7. A sleeve valve engine comprising a cylinder block, single sleeve valves movable within said block in a combined reciprocating and oscillating path, a layshaft extending longitudinally of the engine to one side of the sleeve valves, a crankcase structure housing the layshaft, said layshaft having spaced cranks, links connecting the layshaft cranks and sleeve valves tangentially with the latter for imparting the aforesaid movement to the sleeve valves, and means journalling and supporting the layshaft from and beneath the cylinder block, said journalling and supporting means being positioned above the layshaft and extending longitudinally of the engine at the said side of the sleeve valves, said means engaging the layshaft intermediate the spaced cranks.

8. A sleeve valve engine comprising a cylinder block, single sleeve valves movable within said block in a combined reciprocating and oscillating path, a layshaft extending longitudinally of the engine to one side of the sleeve valves, a crankcase structure housing the layshaft, said layshaft having spaced cranks, links connecting the layshaft cranks and sleeve valves tangentially with the latter for imparting the aforesaid movement to the sleeve valves, means journalling and supporting the layshaft from and beneath the cylinder block, said journalling and supporting means engaging the layshaft intermediate the spaced cranks and being positioned above the layshaft and extending longitudinally of the engine at the said side of the sleeve valves, a drive shaft journalled in the crank case structure, said means engaging the layshaft intermediate the spaced cranks, and a coupling device between the drive shaft and layshaft.

9. An engine of the sleeve valve type comprising in combination, a cylinder block, sleeve valve means operable within the cylinder block, sleeve valve operating mechanism, means driving the sleeve valve operating mechanism, means journalling and sup-

10 15 20 25 30 35 40 45 50 55 60 65 70 75 80 85 90 95 100 105 110 115 120 125 130

porting said sleeve valve operating mechanism with the cylinder block, a crank case structure, and coupling means between the sleeve valve operating mechanism and the driving means releasable on relative separation of the cylinder block and crank case structure.

10. An engine comprising in combination, a cylinder block, valve means for the engine carried by the cylinder block, valve operating mechanism, means driving the valve operating mechanism, means supporting the valve operating mechanism with the cylinder block, a crank case structure, and coupling means between the valve operating mechanism and driving means releasable on relative separation of the cylinder block and crank case structure.

11. An engine comprising in combination with engine valve means and a crankshaft, a cylinder block structure, a casing structure separate from the cylinder block structure, a layshaft journalled with said cylinder block structure means on the layshaft for actuating the valve means, an element adapted to drive the layshaft, said element being journalled with said casing structure actuating means intermediate the crankshaft and said element for driving the element and layshaft from the crankshaft, and coupling means for the layshaft intermediate said element and said layshaft valve actuating means.

12. An engine comprising in combination with engine valve means and a crankshaft, a cylinder block structure, a casing structure separate from said cylinder block structure, a layshaft journalled with said cylinder block structure, means on the layshaft for actuating the valve means, an element adapted to drive the layshaft, said element being journalled with said casing structure, actuating means intermediate the crankshaft and said element for driving the element and layshaft from the crankshaft, and an Oldham coupling intermediate the length of the layshaft.

13. An engine of the sleeve valve type comprising, a cylinder block structure, a second structure separate from said cylinder block structure, sleeve valve means operable within the cylinder block structure, and means for actuating said sleeve valve means including a divided layshaft, coupling means for the layshaft divisions, and means for journalling said layshaft divisions in said structures respectively.

14. An engine comprising a cylinder block, valve means for the engine, a crank case structure, valve actuating means including a layshaft carried by the cylinder block and housed by the crank case structure, and a drive shaft for the layshaft mounted in the crank case structure.

15. An engine comprising a cylinder block, valve means for the engine, a crank case

structure, valve actuating means including a layshaft carried by the cylinder block and housed by the crank case structure, and a drive shaft for the layshaft mounted in the crank case structure, and a coupling intermediate the drive shaft and layshaft releasable on separation of the cylinder block with the valve means, layshaft and valve actuating means as a unit relative to the crank case structure.

In witness whereof I hereunto subscribe my name this 25th day of January, A. D. 1928.
